Fig. 5

FIG. 1 is a front perspective view taken from one side of a hay baler embodying my new design;

FIG. 2 is a side perspective view thereof taken from the side shown in FIG. 1;

FIG. 3 is a rear perspective view thereof taken from the side shown in FIG. 1;

FIG. 4 is a perspective view thereof taken from the side opposite that shown in FIG. 1; and

FIG. 5 is a top plan view thereof, the rear of the bale chute and the front of the drive shaft and hitch frame being broken away for convenience of illustration.

The dominant features of my design reside in the full line portions of the drawings.

I claim:

The ornamental design for a hay baler as shown and described.
